Primary Examiner — Prabhakar Deshmukh*(74) Attorney, Agent, or Firm* — Osha Liang LLP(57) CLAIM

The ornamental design for a digital audio disc player for automobile, as shown and described.

DESCRIPTION

FIG. 1 is a perspective view of front, top and left side of a digital audio disc player for automobile showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown are included for the purpose of illustrating the unclaimed portions of a digital audio disc player for automobile and form no part of the claimed design.
